UNITED STATES PATENT OFFICE.

THOMAS I. RANKIN, OF PHILADELPHIA, PENNSYLVANIA, ASSIGNOR TO THE
ABRAM COX STOVE COMPANY, OF SAME PLACE.

DESIGN FOR A STOVE.

SPECIFICATION forming part of Design No. 19,662, dated February 18, 1890.

Application filed January 27, 1890. Serial No. 338,289. Term of patent 14 years.

To all whom it may concern:

Be it known that I, THOMAS I. RANKIN, a citizen of the United States, and a resident of Philadelphia, Pennsylvania, have invented 5 certain Improvements in Designs for Stove-Plates, of which the following is a specification.

My design for the plate of a stove is fully illustrated in the annexed drawings, in 10 which—

Figure 1 is a face view of the plate; and Fig. 2 is a sectional view on the line 12, Fig. 1.

The essential features of my design are, first, the raised fire-door and the bracket-shaped projection below the same; second, 15 the general design of the fire-door, and, third, the general design of the oven-door.

A is one of the side plates of the stove, B the oven-door, and C the fire-door, which projects outward from the plate A, as shown in 20 the cross-section, Fig. 2. Below the door C is a rim a, in imitation of the outer portion of a shelf, and below this rim is an ornamented bracket D, also projecting from the stove- 25 plate, as shown in the cross-section, Fig. 2, this bracket forming, with the door, the outline shown in relief. The ornamentation on this bracket portion is of a foliated character.

The design of the fire-door C comprises a 30 wide band c at the base of the door, while around the top and sides of the door is a band studded with alternate square and oblong projections e. In the center of the door is a rosette f, surrounded by foliated orna-

ments g. The upper and lower edge of the 35 oven-door and one side of the same are straight, while the opposite side is partly straight and partly curved, and around the top and both sides of the door is a band b, having a series of projections b' thereon. On the lower portion of the door are bars h, with upturned 40 ends, and having at the center a foliated ornament h'. At the top of the door is a panel m, and on the center of the body of the door is a name-plate B', with scroll-border and 45 medallion.

I claim—

1. The within-described design for the side plates of a stove, said design consisting of the oven-door, fire-door, and bracket beneath the 50 latter, substantially as shown and described.

2. In a design for a stove, the design comprising the raised door and the raised bracket beneath the same, substantially as described and shown. 55

3. In a design for a stove, the design for the fire-door C, substantially as shown and described.

4. In a design for a stove, the design for the oven-door B, substantially as shown and de- 60 scribed.

In testimony whereof I have signed my name to this specification in the presence of two subscribing witnesses.

THOMAS I. RANKIN.
